UNITED STATES PATENT OFFICE

2,555,229

ELECTRIC BOTTLE WARMER

Roy R. Fisher, Paris, Ky., assignor to Electric Steam Radiator Corporation, Paris, Ky., a corporation of Michigan

Application April 29, 1949, Serial No. 90,427

3 Claims. (Cl. 219—40)

1

This invention relates to an improved heating device of the type wherein an electric circuit is completed by a quantity of water so that the flow of electric current results in vaporizing the water. The invention is concerned particularly with devices such as bottle warmers and food warmers for baby food and the like.

It is an object of the invention to provide an improved commercial structure which is easier to manufacture from the cost point of view and the assembly point of view and which has distinct operational advantages. Primarily, it is an object to provide a unitary construction wherein the heating well may be formed of one piece and the heating unit inserted therein as a cartridge arrangement.

Another object of the invention is the provision of an electrode shape which prevents shorting of the electrodes in the event of high salt content in residual water. This is accomplished by shaping the electrodes on the opposite faces to widen the water gap as the water level decreases. Other objects and features of the invention as well as details of the construction in operation will be found in the following description and claims.

Drawings accompany the disclosure and the various views thereof may be briefly described as:

Figure 1, a central vertical section through the assembled unit.

Figure 2, a similar section at an angle of 90 degrees to the first section.

Figure 3, a plan view of the unit showing lines 1—1 and 2—2 of the sections of Figures 1 and 2.

Figure 4, a modified construction showing how the outside decorative wall and the inside functional well may be formed of separate pieces.

Figure 5, a sectional view on line 5—5 of Figure 2.

This invention is intended to be an improvement on the device disclosed in my previous application which has matured to Patent 2,433,750 on December 30, 1947. As shown in Figures 1 and 2, the unit is constructed of a single piece of molded plastic. The decorative outer supporting shell 10 blends integrally at the top with the upper rim of the inner functional well 12. The bottom 14 of the inner well 12 is solid, and the bottom surface of this bottom 14 has a horseshoe-like ridge 16 provided with an opening 18 and a center septum 20, see Figure 5.

The heating unit, which is assembled before being inserted into the well, consists of a circular plate 24 which is provided with a central rectangular recess 26. Plate 24 is of ceramic material or other non-conductive, heat resistant sub-

2

stance. Secured to this plate 24 is an arch or bridge-like unit having a top span 28 and legs 30. The legs 30 rest on the edges of plate 24 and screws 32 hold the two parts together. As shown in Figures 1 and 3, the bridge portion 28 is apertured to permit the passage of steam outwardly from the chamber 34 formed by the assembled units.

Resting in the shallow recess 26 of plate 24 on opposite sides thereof are two oblong carbon electrodes, blocks 36, spaced from each other in parallel relation. Transfixing these carbon electrodes together with the plate 24 and the bottom 14 are conductive bolts 40 on which are screwed nuts 42 to tighten the assembly. A sealing disc 44 is interposed between plate 24 and the plastic bottom of well 12.

As shown in Figure 5, the nuts 42 also serve to hold wires 48, respectively connected to the two bolts 40. The septum 20 serves to separate the two bolts and connecting wires which pass outwardly of the base through the gap 18 in the horseshoe formation on the bottom. Referring to Figure 2, it will be seen that the carbon electrodes 36 curve or slant away from each other at 52 as they approach the bottom of the shallow recess 26, thus widening the gap between the electrodes at the bottom. It will be understood that this progressively widening gap can be accomplished by tilting the electrodes as well as by shaping them. A safety disc 60 underlies the unit being fastened to the horseshoe ridge 16 by bolts 62.

In the operation a bottle or other receptacle 35 may be placed on the bridge which has raised crossridges 54 to prevent blocking of the steam holes. After a quantity of water is dumped into the unit and the wires 48 are connected to a wall plug, current will flow between the electrodes 36 and resistance set up between the electrodes will create heat and steam, thus warming whatever is contained in the well 12. Frequently, in some localities the salts within the water will become concentrated as the water level decreases and arcing has been noticed between the electrodes. The particular formation and disposal of the electrodes as described above will prevent this arcing since the gap widens between the parts as the water level decreases.

In Figure 4, I have shown a modified structure in which the outer supporting shell 10A is connected to the inner functional well 12A by a threaded juncture 13, thus permitting the two parts to be made separately if it is desired that

the outer part have a decorative color different from that of the inner part.

It will thus be seen that I have provided a simple and effective heating unit which is completely safe in its operation and which has distinct advantages from the point of view of assembly since the heating unit, consisting of the plate 24 and the bridge 26, may be assembled initially before being inserted into the plastic body.

What I claim is:

1. A nursery bottle warmer of the type having a central well and supporting walls connected to said well at the top and extending outwardly and downwardly to a point below the bottom of the well in which the bottom of the well is formed integrally with the walls thereof and is closed, a heating unit in said well comprising a heat resistant disc, spaced electrodes on said disc, conductors extending through the bottom of said well transfixing said disc and the respective electrodes, means at the top and bottom of said conductors to create a clamping action to hold said electrodes and said plate rigidly in position, a cap-like bottle supporting member shaped to pass steam from and to cover said electrodes, and releasable means extending upwardly from the bottom surface of the heat resistant disc to engage said member removable only from said bottom surface to lock said cap-like member over said electrodes.

2. A nursery bottle warmer as defined in claim 1 in which a sealing member is placed around

said conductors between said bottom and said disc, said clamping means serving to create a seal around said conductors by the compressive force exerted on said member.

- 5 3. A nursery bottle warmer as defined in claim 1 in which the lower surface of the well bottom has embossed portions forming shallow recesses separated from each other, said conductors terminating respectively in said recesses, electrical lead means extending into said recesses through an opening in said embossed portions and fastened to said conductors by said clamping means, and a non-conductive plate means fastened to said embossed portion to close said recesses from the bottom and prevent contact with said lead means and conductors.
